UNITED STATES PATENT OFFICE.

EDWARD A. BUCK, OF WASHINGTON, DISTRICT OF COLUMBIA.

DESIGN FOR A CLOCK-DIAL.

45,448.

Specification for Design.

Patented Mar. 24, 1914.

Application filed January 6, 1914. Serial No. 810,684. Term of patent 3½ years.

To all whom it may concern:

Be it known that I, EDWARD A. BUCK, a citizen of the United States of America, residing at Washington, in the District of Columbia, have invented a new, original, and ornamental Design for Clock-Dials, of which the following is a specification, reference being had to the accompanying drawing, forming a part thereof.

In the drawing: Figure 1 is a plan view

of a clock dial showing my new design. Fig. 2 is an edge view.

I claim:

The ornamental design for a clock dial, as shown.

EDWARD A. BUCK.

Witnesses:

J. D. YOAKLEY,
J. EDWARD ESPEY.
